UNITED STATES PATENT OFFICE.

CHARLES DIEHL, OF EGG HARBOR CITY, NEW JERSEY.

SMOKE-PIPE COLLAR.

1,006,448.

Specification of Letters Patent. Patented Oct. 17, 1911.

Original application filed July 29, 1910, Serial No. 574,476. Divided and this application filed January 7, 1911. Serial No. 601,267.

To all whom it may concern:

Be it known that I, CHARLES DIEHL, a citizen of the United States, residing at Egg Harbor City, in the county of Atlantic and 5 State of New Jersey, have invented certain new and useful Improvements in Smoke-Pipe Collars, of which the following is a specification.

My invention relates to improvements in 10 smoke pipe collars, and more particularly to devices of this kind, adapted to securely hold the smoke pipe in the chimney opening, the object of the invention being to provide a collar of this character, which can be 15 placed in position and removed without disturbing the normal position of the smoke pipe.

This application is filed as a division of 20 my application filed July 29, 1910, and given Serial No. 574,476.

With this object in view, the invention consists in certain novel features of construction, and combinations and arrangements of parts as will be more fully herein- 25 after described and pointed out in the claim.

In the accompanying drawings, Figure 1, 30 is a broken view in longitudinal section illustrating my improvements. Fig. 2, is a view in section on the line 2—2 of Fig. 1.

1 represents a chimney, and 2 an opening therein.

3 is a smoke pipe which is provided near its end with an annular inwardly projecting groove 4, said smoke pipe projecting into the opening 2 as shown in Fig. 1.

My improved collar is made in two sections 5, 5, each of semi-circular form, adapted to fit against the outer face of the chimney 1, and secured thereto by means of 40 screws 6. Each half section 5, 5, is provided with a semi-circular flange 7, which fits into and projects into the opening 2, and each

section is also provided with an annular internal flange 8, projecting into the groove 45 4 of pipe 3, so that when the ring sections are fastened on to the pipe from opposite sides, and then pushed into the opening 2, said pipe 3 will be securely held to the chimney, after said ring sections are secured by 50 screws 6. It will, therefore, be noted that while the ring sections are readily inserted and removed, that they will most effectually prevent any escape of the smoke pipe from 55 the chimney when once in position.

Various slight changes might be made in the general form and arrangement of parts described, without departing from my invention, and hence I do not limit myself to the precise details set forth, but consider 60 myself at liberty to make such changes and alterations as fairly fall within the spirit and scope of the appended claim.

Having thus described my invention what I claim as new and desire to secure by Letters Patent is:—

The combination with a pipe section having an annular groove therein, of a collar comprising two half sections, an inwardly projecting curved flange on each half section, which when said sections are together, is of a diameter to snugly fit the chimney opening, and inwardly projecting flanges on said sections adapted to project into the groove in the pipe, said collar supporting 70 the pipe centrally in the chimney opening and held by reason of the snug fit in the opening in locked engagement with the pipe, substantially as described.

In testimony whereof I have signed my 80 name to this specification in the presence of two subscribing witnesses.

CHARLES DIEHL.
